BURIAL CASKET CONSTRUCTION

Raymond F. Staack, Oakland, Calif.

Application March 6, 1935, Serial No. 9,637

7 Claims. (Cl. 27—10)

The invention relates to the design and fabrication of burial caskets constructed of wood and the like, and relates more particularly to the manner and arrangement of connecting and associating the side and end walls of the casket.

An object of the invention is to provide a connection for the side and end walls of the casket, which will insure an effective securing of such parts together and at the same time will afford greater aesthetic qualities for the external appearance of the casket without adding to the cost of construction of the casket.

Another object of the invention is to provide a construction of the character described, which lends itself to the creation of many different designs of caskets.

A further object of the invention is to provide an insert member between the end and side walls of the casket, which arranges for both a direct and indirect connection of said walls so as to simultaneously afford the structural advantages of the one type of connection and the aesthetic advantages of the other form of connection.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is an end view of a burial casket constructed in accordance with my invention.

Figure 2 is a fragmentary plan view of one end of the casket with the cover omitted.

Figure 3 is a fragmentary vertical sectional view of the casket taken on the line 3—3 of Figure 2.

Figure 4 is a view similar to Figure 3, taken on the line 4—4 of Figure 3.

Figures 5, 6 and 7 are views corresponding to Figures 1, 2 and 3 respectively but showing a somewhat modified construction.

As disclosed in the embodiment of the invention first referred to, the casket 2 comprises side walls 3, end walls 4—only one of which is here shown, and a bottom wall 5. Each of the walls is preferably constructed of wooden boards 7 with their adjoining edges inter-engaged through tongue and groove formation. In the drawing the casket is shown provided with a cover 8, but such

cover comprises no part of the novel subject matter of the present case.

Usually in the construction of caskets, the side and end walls are connected by sections or inserts which form beveled corners for the casket. Heretofore these sections have invariably been made of quadrangular form and inserted between the walls so as to completely separate the adjacent ends of the walls. Such a construction permits connecting the side and end walls only indirectly, and obviously when the parts are fastened together, the structure presents less rigidity than where the walls are secured together in right-angular relation and with the edges of a side wall abutting directly against the edge of the adjoining end wall. On the other hand, the latter construction, as will be readily evident, renders the appearance of the casket box-like and makes relatively difficult and expensive the ornamentation of the casket to relieve such appearance. In accordance, however, with my invention, the insertable section is of such form and so arranged for positioning between the side and end walls, that in one and the same construction, said walls may be directly connected at the corners of the casket, and at the same time such corners will have the desired bevel.

In carrying out my invention, I do not eliminate the use of an insert section, but I employ a section 9 which is in the form of a triangle rather than a quadrangle, and I so position the section between the edges of the adjacent walls, that at least at one point said edges may abut whereby such walls may be directly and securely fastened together therat. It should be here noted that while I prefer, for the sake of simplicity, to use a triangular shaped section for the corner, it should be understood that other shapes of sections may be used so long as they may be inserted between the walls with at least a portion of the latter in substantial engagement. In this connection, it can be seen that even a four-sided section may be used.

It will be understood that the adjacent edges of the walls are cut to exactly accommodate the section to be inserted, and as will be seen from the drawing illustrating the embodiment being described, the section 9 is positioned with one corner 10 lowermost and with the side 12 opposite thereof flush with and forming a continuation of the upper edge 13 of the side and end walls. Also in this embodiment, the corner 10 of the section terminates short of the lower edge 14 of the walls so that a considerable portion of the edges of the walls may be in abutting rela-

tion. This arrangement not only permits a more rigid structure, but makes easy the application of a base mold all around the casket without the use of separate inserts for the corners.

5 The insert section may be secured in position by the usual clamp-nails 16 or other fastening means, nails being utilized at each corner of the section for securing the section to the walls, and nails being used adjacent the bottom of the

10 walls for securing these walls directly together. Desirably a top mold 17 is applied around the exterior of the casket along the upper edge thereof, and as will be clear from Figures 2 and 4, a filler piece 18 is preferably inserted between

15 the section and the portion of mold overlying same, in order that such mold portion may be readily secured to the section in registering relation with the portions of the mold covering the side and end walls.

20 It will now be evident that the casket formed in accordance with my invention will have practically the same sturdiness as one formed with square corners, yet at the same time, as will be clear from Figure 1, it affords the casket an inherent design both dignified and conducive to ready elaboration if desired. It will also be seen that with the embodiment of the invention above described, there may be used with the casket a type or design of cover having beveled corners

25 21, such as are adapted for use with the full beveled corner casket previously referred to.

In Figures 4 to 7 inclusive, I have shown a form of the invention which may in one sense be considered a counterpart of the form of the invention first described. As here shown, the triangular form of the corner section 23 is still employed, but is arranged so that the corner 24 thereof meeting the abutting edges of the side and end walls, is uppermost and is preferably 30 extended to the top edge of the casket. The section 23 is in this form of the invention made co-extensive vertically with the side and end walls so that the section side 26 opposite the corner 24 rests directly upon the bottom wall 27 of the

40 casket. In this construction it will thus be evident the direct connection of the side and end walls is effected at the top of the casket, while indirect connection of such walls is afforded at the bottom through the intervention of the insert 23.

I claim:

1. In a burial casket, separate side and end walls having their adjacent edges connected and abutting at a point to form a substantially square corner for the walls thereat, said edges being spaced at other points, and a wall section fitting in the space between said edges and forming thereat a beveled corner for said walls.

2. In a burial casket, separate side and end walls having their adjacent edges abutting at one portion and spaced at the remaining portion, a wall section fitting in the space defined between said edges and forming for said walls a beveled corner thereat, means directly connecting together the abutting portions of the side and end walls, and means connecting together said section with each of said walls.

3. In a burial casket, a bottom member, separate side and end walls secured to said member having their adjacent edges in substantially abutting relation at said member to form a substantially square corner for said walls thereat and the remaining portion of said edges spaced to define a space, and a wall section fitting in said space and extending to the upper edge of said walls to provide a beveled corner for said walls.

4. In a burial casket, a bottom member, side and end walls secured thereto and extending upwardly therefrom and having their adjacent side edges spaced from each other at the upper portion and in abutment at the lower portion to define thereat a substantially square corner for said walls, a triangular wall section fitting in the space between said side edges to provide a beveled corner for said walls increasing in magnitude from said abutting portion to the top of 20 said walls, and a base mold for said walls providing a substantially square corner at the abutting portions of said walls.

5. In a burial casket, a bottom member, side and end walls secured thereto and extending upwardly therefrom and having adjacent side edges spaced from each other at the upper portion and in abutment at the lower portion to define thereat a substantially square corner for said walls, a triangular wall section fitting in the space between 25 said side edges to provide a beveled corner for said walls increasing in magnitude from said abutting portion to the top of said walls, means securing directly together the walls at the abutting portion, means securing said section to each of said walls, a base mold for said walls providing a substantially square corner at the abutting portion thereof, a top mold for said walls, a corresponding mold for said section registering with the top mold on the walls, and a 30 filler interposed between said section and the top mold portion thereover.

6. In a burial casket, a bottom member, side and end walls in substantially right angular relation to each other extending upwardly from 45 said member and having their side edges in substantially abutting relation at the top of the walls and in spaced relation at the lower portion, a wall section fitting in said space forming a beveled corner for said walls thereat, means securing said walls together at the abutting portion, and means securing said section to said walls and member at the spaced portion.

7. In a burial casket, a bottom member, side and end walls in substantially right angular 55 relation to each other extending upwardly from said member and having their side edges in substantially abutting relation at the top and in spaced downwardly diverging relation for the remaining portion to thereby define with said 60 bottom member a triangular space and a triangular wall section fitting in said space to provide a beveled corner for said walls of increasing magnitude from the abutting edges to said member.

RAYMOND F. STAACK.
